UNITED STATES PATENT OFFICE.

EARL CANEDY, OF CHICAGO HEIGHTS, ILLINOIS, ASSIGNOR TO KEWANEE WATER SUPPLY COMPANY, OF KEWANEE, ILLINOIS, A CORPORATION OF ILLINOIS.

INTERNAL-COMBUSTION ENGINE.

1,156,886.

Specification of Letters Patent.

Patented Oct. 19, 1915.

Application filed December 7, 1910. Serial No. 596,024.

To all whom it may concern:

Be it known that I, EARL CANEDY, a citizen of the United States, residing at Chicago Heights, county of Cook, and State of Illinois, have invented new and useful Improvements in Internal-Combustion Engines, of which the following is a specification.

My invention relates to improvements in internal combustion engines, with especial reference to pumping engines.

The objects of my invention are to provide a compact structure and to provide efficient governing mechanism, which will not only regulate the speed of the engine more efficiently than the governors heretofore employed, but will have increased durability in those parts which in the ordinary engine are most subject to wear and breakage.

A further object of my invention is to provide improved circuit closing mechanism for the primary or battery circuit, which will be controlled in part by the governor in such a manner that the circuit will be automatically broken, while the speed of the engine is being checked by the operation of the governor.

In the following description, reference is had to the accompanying drawings, in which—

Figure 1 is a side view of a pumping engine embodying my invention. Fig. 2 is a plan view of the same. Fig. 3 is an enlarged detail plan view of the governing mechanism and spark controlling device. Fig. 4 is a rear elevation of the same, part in section. Fig. 5 is a detail view in vertical section, showing the cam shaft and its actuating wheel, circuit closer and timing lever. Fig. 6 is a diagram of the electrical connections. Fig. 7 is a detail view of the outer side of the fly wheel, showing the spring retracted crank.

Like parts are identified by the same reference characters throughout the several views.

The various parts of my improved pumping engine are so organized as to provide a compact structure, in which all rotating parts are completely balanced, the engine being of such form that it can be mounted upon a bed 1, which is supported in a raised position by a frame 2. The piston in the engine cylinder 4 transmits its motion to the pump 5, through the connecting rod 6,

crank 7, crank shaft 8, pinion 9, gear wheel 10, driven crank shaft 11, crank 12 and connecting rod 13 of the pump. The engine cylinder 4 and pump cylinder 5 are parallel with each other and mounted upon the same end of the bed 1.

The specific design of the engine proper and also that of the pump is not essential. The valve mechanism of the engine is located in an auxiliary casing 14, which may be formed integrally with the engine cylinder, and which is preferably disposed between the engine cylinder 4 and pump cylinder 5. The valves, together with the mixing chamber and exhaust ports, are not specifically illustrated, but it will be understood that these parts may be of any ordinary construction. The valve stem 16 of the exhaust valve, however, projects through a bushing 17, which is removably inserted in suitable apertures in the casing 14, so that when the bushing becomes worn, it can be removed and replaced by a fresh bushing, in which the valve stem 16 will snugly fit. The exhaust valve stem 16 is provided with a collar 20, and between this collar 20 and a shoulder 22 on the casing, a spring 23 is interposed which, by its reaction, seats the exhaust valve as hereinafter explained. Motion is normally transmitted from the crank shaft 8 to the valve stem 16 of the exhaust valve, through the pinion 24, gear wheel 26, cam shaft 27, cam 28, (Fig. 5), and cam actuated rod 29. The rod 29 is provided with a collar 30, against which a cushion spring 31 seats with the other end of the spring bearing against a sleeve 32 connected with the collar 20, and embracing the abutting ends of the rod 29 and valve stem 16. When the cam 28 pushes upon the rod 29 in the direction of rod 16, the pressure of the rod 29 upon the spring 31 is transmitted to the sleeve 32 and collar 20, whereby pressure is applied to the spring 23 before the rod 29 comes into actual contact with the valve stem 16. This prevents the rod 29 from hammering the end of valve rod 16.

The governing weights 35 are supported by pivot pins 36 on the respective sides of the shaft 8 by means of a collar 37, which is rigidly secured to the shaft, and provided with suitable arms 38, through which said pivot pins 36 extend. A sleeve 40 is mounted loosely upon the crank shaft 8 and extends between the pivot pins 36 to a point 110

within the arms of the governing weights, where this sleeve is provided with a flange 42. A collar 44 is mounted upon the sleeve 40, and is free to rotate thereon. The governing weights are provided with inwardly projecting arms 46, which extend into proximity with the sleeve 40 and are provided with bearing faces 48 between which and the flange 42, the loose collar 44 is interposed. Projections 47 on the collar 44 engage the ends of the governing arms 46, whereby the collar is positively actuated from the governor arms and rotates with them, thus avoiding all wear except upon the contacting faces of the collar 44 and flange 42. On the opposite side of the collar 37 from that occupied by the sleeve 40, the governing weights 35 are connected by springs 50, one on each side of the shaft 8, and when the speed of the shaft 8 is such that the weights 35 move outwardly by centrifugal force against the tension of the springs 50, the bearing surfaces 48 of the arms 46 will bear upon the collar 44, and the motion thus developed, will be transmitted through said collar to the flange 42 and sleeve 40, moving the latter longitudinally along the shaft 8. This movement is utilized to control the speed of the engine. The speed of the engine is directly controlled by a trip lever 55, acting in connection with a trip catch 56 to prevent the retractive movement of the rod 29 and hold the exhaust valve open during the suction stroke. The engine is of the common type, in which the gasoline is drawn into the mixing chamber by suction and therefore when the exhaust valve is held open, no gasoline will be delivered to the mixing chamber. The trip catch 56 is fast upon the rod 29 and is provided with a notch 60, having an inclined or beveled seating face for the trip lever latch plate 62, whereby when the latch plate 62 moves into the path of the adjacent margin of the catch plate 56, it will readily seat in said notch 60. The trip lever 55 is pivotally supported intermediate of its ends, upon the frame member 61, and the power arm of the lever 50 extends above and across the line of the shaft 8 with the extremity loosely engaged by a guide pin 65, said pin preferably extending through a hole in this arm of the lever. The pin 65 is provided with a nut or head 67, between which and the extremity of the lever 55, a spring 68 is interposed, which spring tends to hold the lever 55 with the latch plate 62 in a retracted position. The lever 55 is provided with an arm 70, which 55 loosely engages in a recess or slot 72 in the governor actuated sleeve 40, (Fig. 3.) This slot 72 is of sufficient size with reference to the arm 70, that the trip lever 55 is permitted to move independently into a seating engagement in notch 60, whenever the gover-

nor sleeve 40 has moved the trip lever to a position where the latch plate 62 will be struck by the margin of the catch plate 56. I regard this slight independent movement as an important feature of my invention, since otherwise the trip latch 62, in moving to full seating engagement in the notch 60, would have to overcome the inertia not only of the trip lever 55, but of the sleeve 40, and the movement of the sleeve 40 thus produced, would suddenly relieve a portion of the resistance to the pressure of the governing weights with a resultant shock before equilibrium could be restored.

The electrical control of the engine will be easily understood from the diagrammatic view furnished in Fig. 6, taken in connection with Figs. 1 and 5. The batteries 80 are located underneath the bed 1 and within the frame 2, which is preferably an open frame with a floor in one portion thereof, adapted to support the batteries and the gasoline tank 81. The usual spark coil 83 and spark plug 84 are employed for the ignition of the gases in the engine cylinder. The primary circuit of the batteries is in my improved construction established through the conductor 86, the primary of the spark coil 83, conductor 87, contact clip 88, fork 89, the frame of the engine, ball contact 90, timer contact 91, timer lever 92, and conductor 93.

Two of the features of the above described battery circuit require more specific description, and are believed to be novel. One of these is the provision of the ball switch 90 in connection with the timer contact 91. Referring to Fig. 5, it will be observed that the ball 90 is seated in a bushing 95 mounted in the web of the gear wheel 26. This bushing 95 has its margins inturned at 97 to form a retaining socket for the ball, which is held in said socket by a spring 98 with the periphery of the ball projecting slightly through the aperture between the inturned margins 97 of the bushing. A timer lever 92 is provided with a removable contact piece 91, having a rounded surface with which the ball 90 contacts, once during each revolution of the wheel 26. The timer lever 92 is formed integrally with a sleeve 99, which extends into the frame bearing 100 and has sufficient frictional contact with the bearing member 100 to hold the timer lever in any desired position of adjustment. It will of course be understood that the contact member 91 is insulated from the lever 92. A spring arm 102, however, is electrically connected with this contact member 91 and may be manually pressed against a contact projection 103, to close the circuit whenever it is desired to test the igniter, thereby avoiding the necessity of cranking the engine for this purpose. In order to close the circuit, however, it is necessary that the rod 29 be

in retracted position with the exhaust valve closed and the fork 89, (Fig. 6) in contact with the contact plate or clip 88. It therefore follows that when the trip lever is in 5 position with the latch 62 engaging catch 56 to hold the exhaust valve open, the fork 89 will be kept out of engagement with the contact clip 88 and thus prevent sparking, except when explosive charges are delivered 10 to the engine cylinder.

Referring to Fig. 7, it will be observed, that the fly wheel 104 of my improved engine, is provided with a crank arm 105 having a hinged connection with the fly wheel 15 at 106, which permits an adjustment of the crank arm to a position of use at right angles to the fly wheel, or to a position of non use, in which the crank arm is folded into a recess 107 formed in the side of the fly wheel. 20 A spring 108, coiled about the pintle 106, tends to hold the crank arm in the position of non-use and automatically restores it to such position after it has been manually pulled out and used. This crank arm has 25 a weight which equals the weight of the metal which would occupy the recess 107, if this feature of my invention were omitted. The presence of the crank arm, therefore, does not destroy the balance of the fly wheel. 30 This feature of balancing the more rapidly rotating parts of an engine, is an important one, and I therefore arrange the governing weights 35 so that they will be accurately balanced upon the shaft 8. I also provide 35 counterweights 109 upon the crank 7, (Fig. 1), for the same purpose.

While I have described my invention with specific reference to pumping engines, it will be understood that the improvements 40 are largely applicable to any form of internal combustion engines, or any apparatus of the general class to which such engines relate.

Having thus described my invention, what 45 I claim as new, and desire to secure by Letters Patent, is:—

1. In apparatus of the described class, the combination with an internal combustion engine, including a crank shaft, valve operating and igniting mechanism, of a set of speed governing weights fulcrumed to said shaft and adapted to rotate therewith, a non rotatable member movable along the shaft and provided with a flange encircling 50 the shaft, a loose collar encircling said member and shaft and adapted to be pushed against said flange, arms integrally connected with the governing weights and projecting transversely of the shaft 55 into a position to engage and actuate said collar in the direction of said flange when the governing weights move outwardly, and a trip lever loosely connected with said longitudinally movable member 60 and adapted to control the speed of the en-

gine, said longitudinally movable member and trip lever being otherwise free to move independently of the valve operating mechanism.

2. In apparatus of the described class, the combination with an internal combustion engine and shaft, of a sleeve loosely mounted thereon, and movable longitudinally, a collar loose on the sleeve, a flange fast on the sleeve, against which the collar may move, 75 a set of governing weights pivotally supported from the shaft, and adapted to actuate the collar and sleeve, a projection on said collar loosely engaged by the governing weights, to rotate the collar, and means for 80 transmitting the motion of said sleeve to control the speed of the engine.

3. In apparatus of the described class, the combination with an internal combustion engine including an exhaust valve, ignition circuit and piston operated shaft, of a sleeve loosely mounted on the shaft, and movable longitudinally, a collar loose on the sleeve, a flange fast on the sleeve, against which the collar may move, a set of governing weights 90 pivotally supported from the shaft, and adapted to actuate the collar and sleeve, a projection on said collar loosely engaged by the governing weights, to rotate the collar, and means for transmitting the motion of said sleeve to control the speed of the engine, said motion transmitting means comprising a member for opening the exhaust valve, a trip lever loosely engaged by said sleeve and adapted when actuated by the 95 sleeve to speed checking position to engage said member and hold the exhaust valve of the engine in open position, and means connected with said trip lever for controlling an igniter circuit. 100

4. In apparatus of the described class, the combination with an internal combustion engine provided with an exhaust valve, of an engine shaft, a sleeve loosely mounted thereon, and movable longitudinally, a collar loose on the sleeve, a flange fast on the sleeve, against which the collar may move, a set of governing weights pivotally supported from the shaft, and adapted to actuate the collar and sleeve, a projection on said collar 110 loosely engaged by the governing weights to rotate the collar, and means for transmitting the motion of said sleeve to control the speed of the engine, said motion transmitting means comprising a latch and catch trip mechanism controlling the exhaust valve of the engine, and including a lever loosely engaged by said sleeve, said lever being free to move independently to a limited extent 115 when being actuated to speed checking position.

5. In an internal combustion engine, having a valve controlling rod provided with a catch plate, the combination with the catch plate of a spring retracted trip lever having 125 130

a beveled seating end, adapted to engage in a notch in the catch plate, and speed controlled means for actuating said lever into engagement with the catch plate; said speed controlled means including a free moving non-rotatable sliding member provided with a slot in which the trip lever loosely engages; said trip lever being free to move independently of the actuating means into the catch plate notch when its beveled end is engaged by said plate.

6. In an internal combustion engine having a valve controlling rod provided with a recessed catch plate, the combination with the catch plate, of a trip lever having a seating end adapted to engage the catch plate, a rotary crank shaft, centrifugal governing weights mounted thereon, and a non-rotatable sleeve on said shaft, movable longitudinally by the governing weights; said sleeve having a slot therein and said trip lever having an arm loosely engaged in said slot and free to move to a limited extent therein.

25 7. In an internal combustion engine having a valve controlling rod provided with a recessed catch plate, the combination with the catch plate, of a trip lever having a seating end adapted to engage the catch plate, a rotary crank shaft, centrifugal governing weights mounted thereon, and a non-rotatable sleeve on said shaft, movable longitudinally by the governing weights; said sleeve having a slot therein and said trip lever having an arm engaged in said slot, together with a spring cushion normally holding the trip lever with its seating end out of seating position.

8. In an internal combustion engine the combination with an igniter circuit and a valve controlling rod provided with a recessed catch plate, of a trip lever having a seating end adapted to engage the catch plate, a rotary crank shaft, centrifugal governing weights mounted thereon, and a non-rotatable sleeve on said shaft, movable longitudinally by the governing weights; said sleeve having a slot therein and said trip

lever having an arm loosely engaged in said slot and free to move to a limited extent 50 therein, together with means connected with the valve controlling rod for partially connecting up the igniter circuit.

9. In an internal combustion engine, the combination with an igniter circuit, valve 55 and a valve controlling rod provided with a recessed catch plate, of a trip lever having a seating end adapted to engage the catch plate, a rotary crank shaft, centrifugal governing weights mounted thereon, and a 60 non-rotatable sleeve on said shaft, movable longitudinally by the governing weights; said sleeve having a slot therein and said trip lever having an arm loosely engaged in said slot and free to move to a limited extent 65 therein, together with means connected with the valve controlling rod for connecting up a portion of the igniter circuit simultaneously with the closing of the valve, a cam shaft for normally actuating said rod, 70 and a circuit closer operatively connected therewith for completing the igniter circuit once during each revolution of the cam shaft, except when the trip lever is in engagement with said catch.

75 10. An internal combustion engine, including the combination of a shaft, a set of governing weights pivotally connected therewith and adapted to move outwardly by centrifugal force, tangentially projecting arms connected with said governing weights, a loose collar encircling said shaft in a position to be engaged by said arms, an engine controlling trip, and a freely moving sleeve loosely connected with the trip 80 and adapted to be frictionally engaged and actuated by said collar, said sleeve being otherwise free and sensitive to outward movements of the governing weights.

In testimony whereof I affix my signature 90 in the presence of two witnesses.

EARL CANEDY.

Witnesses:

F. G. ROGERS,
Miss A. REGAN.
